UNITED STATES PATENT OFFICE.

CHARLY A. THORSLEND, OF BERWYN, ILLINOIS.

RAILWAY SAFETY APPLIANCE.

1,105,863.

Specification of Letters Patent.

Patented Aug. 4, 1914.

Application filed May 19, 1913. Serial No. 768,525.

To all whom it may concern:

Be it known that I, CHARLY A. THORSLEND, a citizen of the United States, and a resident of the city of Berwyn, county of Cook, and State of Illinois, have invented 5 certain new and useful Improvements in Railway Safety Appliances, of which the following is a specification.

My invention relates to railway safety 10 appliances and more particularly to devices which operate in conjunction with signaling devices or semaphores to cut off power from a locomotive or other means furnishing motion to a train.

15 The object of this improvement is to provide a simple device of the character mentioned which will effectively cut off the power from a train or car when the signaling device is set in a position indicating 20 danger, and be in inoperative position when the signaling device is in its "clear" position.

25 The invention consists in the combinations and arrangements of parts hereinafter described and claimed.

The invention will be best understood by reference to the accompanying drawing forming a part of this specification, and in which,

30 Figure 1 is a plan view of a broken portion of a railway equipped with my device, Fig. 2 is an elevation of the same, Fig. 3 is a view taken on line 3—3 in Fig. 1, and Fig. 4 is a section taken on line 4—4 in Fig. 1.

35 The preferred form of construction as illustrated in the accompanying drawing comprises a railway of conventional construction made up of rails 5 and cross ties 6. Certain of the cross ties 6 are extended beyond others to afford a base for the signaling and tripping device included in the construction. Situated on two of the extended ties 6 is an upright post 7 carrying a signaling arm 8 and constitutes a signaling device 40 or semaphore now in conventional use. The signaling arm 8 of the semaphore is operated by means of a connecting rod 9 which extends downwardly through post 7 and connected with one arm of the bell crank lever 10.

45 50 55 10. The other arm of bell crank lever 10 is connected with a connecting rod 11 which extends to a tower, or other place from which the semaphore is operated, not shown. The connecting rod 11 is extended beyond the semaphore to a tripping device which embodies my invention. This tripping de-

vice consists of a stand 12 upon which is secured a head 13. The head 13 is provided with an opening in one side through which is slidably mounted a member 14. Said member 14 is provided with a slot 15 at its inner end and the slot 15 engaged by one arm of a bell crank lever 16. The bell crank lever 16 is pivoted in head 13 and has its other arm connected by means of a connecting rod 17 with a second bell crank lever 18 which is pivoted at the lower end of stand 12. The other arm of bell crank lever 18 is connected with connecting rod 11 in a manner to be operated simultaneously with the signaling arm 8 of the semaphore. Positioned at about the same distance from the semaphore as the signaling device already described is a second signaling device made identical with the one already mentioned 60 and connected with the connecting link 11 in the same manner. The second signaling device is provided so that a train, not shown, running over rails 5 from either direction will be operated on by a member 14 at a 65 given distance from the semaphore.

In the construction shown the connecting rod 11 extends to the switchman's tower, not shown, but it is understood that any form of means may be used to operate the semaphore 70 which is desired. In case other means are used to operate the semaphore the connecting rods 11 are used to connect the bell crank levers 18 with bell crank lever 10 in order to cause simultaneous operation of the 75 two tripping devices upon operation of the 80 signaling device or semaphore.

While I have illustrated and described the preferred form of construction for carrying my invention into effect, this is capable of 85 variation and modification without departing from the spirit of the invention. I, therefore, do not wish to be limited to the precise details of construction set forth, but desire to avail myself of such variations and 90 modifications as come within the scope of the 95 appended claims.

Having described my invention what I 100 claim as new and desire to secure by Letters Patent is:

1. A device of the class described comprising a signaling device; a stand positioned at a distance from said signaling device; an elongated member slidably mounted in said stand and having one end extending laterally therefrom and its inner end provided with a laterally extending slot; a 110

crank arm journaled in said stand and engaging said slot; and an operative connection between said crank arm and said signaling device, substantially as described.

- 5 2. A device of the class described comprising a signaling device; a stand positioned at a distance from said signaling device; a power switch tripping member slidably mounted in said stand and having a
10 portion extending therefrom, there being a laterally disposed slot at the inner end of said member; a crank arm journaled in said stand and engaging said slot; a bell crank

lever pivoted in said stand; a connecting rod connecting one arm of said bell crank lever 15 with said crank arm; and a connecting rod connecting the other arm of said bell crank lever with said signaling device, substantially as described.

In testimony whereof I have signed my 20 name to this specification in the presence of two subscribing witnesses.

CHARLY A. THORSLEND.
